UNITED STATES PATENT OFFICE.

WILLIAM C. SCHNEIDER, OF VERDON, NEBRASKA.

BABY'S CHAIR.

Application filed June 2, 1926. Serial No. 113,246.

This invention relates to nursery devices to facilitate the care of infants when they reach the stage to sit and creep and the same consists of a chair devoid of legs, so as 5 to be placed with the seat or bottom in direct contact with the floor or other support.

The invention further consists of a chair and a tray therefor to confine the infant within certain limits and to receive sundry 10 articles of food, toys or the like.

While the drawings illustrate the preferred embodiment of the invention, it is to be understood that in adapting the means to meet specific needs and requirements, the 15 design may be varied and such other changes in the many details of construction may be resorted to within the scope of the invention as claimed, without departing from the spirit thereof.

20 For a full understanding of the invention and the merits thereof, reference is to be had to the following description and the drawings hereto attached, in which,—

Figure 1 is a perspective view of a baby's 25 chair embodying the invention, the outer portion of the arm rest on the near side being broken away to show more clearly the means for holding the tray in place.

Figure 2 is a front view of the chair, a 30 portion of the front of the tray being broken away, and

Figure 3 is an enlarged detail sectional view on the line 3—3 of Figure 2.

Corresponding and like parts are referred 35 to in the following description and indicated in the several views of the drawings by like reference characters.

The chair consists of a box-like body and is devoid of legs whereby to be placed directly upon the floor or other support, and as shown, the same comprises a bottom 1, sides 2, and a back 3, the body being open in front and at the top, as indicated most clearly in Figure 1 of the drawings. The 40 rear portions of the sides 2 are extended upwardly a short distance to provide ample support for the child, the front portions being low so that the arms may move freely thereover. Rests 4 project laterally from 45 the upper edges of the sides 2 and constitute supporting means for the arms of the child, as well as serving to reinforce the sides 2 and provide guards for the spring catches 5 provided as fastening means for securing 50 the tray when placed in position. The parts

4 are in the nature of lateral wings and are braced by means of blocks 6, which are secured to the sides 2 in the angle formed between the parts 2 and 4.

The tray 7 consists of a plate or board of 60 a width slightly greater than the distance between the sides 2 of the body of the chair, and is adapted to slide in grooves 8 formed in the inner walls of the sides 2 adjacent the upper edges thereof, the portions of the 65 sides extending above the tray 7 forming in effect enclosing sides to prevent lateral displacement of articles which may be placed on the tray. A cross strip 9 attached to the front of the tray 7 extends beyond the sides 70 of the latter, so as to overlap the front ends of the sides 2 and come between the extensions of the arm rests 4, as indicated most clearly in Figure 1, and the spring catches 75 5 are attached to the cross piece 9 and extend rearwardly along the outer side of the parts 2 and engage shoulders or stops provided by notches 10 formed in the sides 2 adjacent the top edges thereof. The spring catches 5 are attached to the front of the 80 cross piece 9 and are bent to extend rearwardly and when the tray is in position the sides 2 of the body are comprised between the tray and the catches 5, as shown most clearly in Figure 3, hence it will be readily 85 appreciated that outward displacement of the sides 2 is prevented. It is also observed that the catches 5 are disposed beneath the arms 4 and are protected thereby, so that the infant may not readily release the tray 90 or meet with injury by contact of the hands with the catches.

When the child is placed in the chair its body is supported by the back 3 and rear portions of the sides 2, and when the tray 95 is in position, forward movement of the child is limited, but the feet are free because of the open front. The device may be placed directly upon the floor, or upon an ordinary chair or upon the seat of a vehicle, such as an automobile, or upon the floor of the latter, and the child may be fed and amused by placing food and toys upon the tray as will be readily understood.

Having thus described the invention, 105 what I claim is:

A box-shaped body comprising a bottom, a back and sides extended upwardly from the bottom, the sides having grooves in their inner faces adjacent the top edges and slats 110

in their outer faces, a tray slideable in said grooves between the sides and having extensions at its front to engage the sides and limit the inward movement of the tray, 5 catches connected to the front of the tray and extending along the outer faces of the sides and engaging said seats, the sides of

the body being held between the catches and tray, and wings extended outwardly from the upper portions of the sides to form arm 10 rests and constituting guards to extend over the said catches.

In testimony whereof I affix my signature.
WILLIAM C. SCHNEIDER. [L. S.]

CERTIFICATE OF CORRECTION.

Patent No. 1,647,200.

November 1, 192

WILLIAM C. SCHNEIDER.

It is hereby certified that error appears in the printed specification of the above numbered patent requiring correction as follows: Page 1, line 110, in the claim, for the word "slats" read seats; and that the said Letters Patent should be read with this correction therein that the same may conform to the record of the case in the Patent Office.

Signed and sealed this 8th day of September, A. D. 1936.
